REFRIGERATOR

John T. Whalen, New York, N. Y.

Application June 10, 1936, Serial No. 84,414

9 Claims. (Cl. 211—143)

The invention relates to new and useful improvements in refrigerators and more particularly to such improvements looking to increasing the capacity and accessibility of household refrigerators.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a perspective view of a refrigerator showing one form of the invention;

Fig. 2 is an enlarged fragmentary vertical section on the line 2—2 of Fig. 1;

Fig. 3 is a detached perspective view of the support having track-ways;

Fig. 4 is an enlarged transverse section on the line 4—4 of Fig. 3;

Fig. 5 is a detail elevation of one of the article-supporting or storing members;

Fig. 6 is a fragmentary elevation showing a different form of the invention;

Fig. 7 is a detached, perspective view, on an enlarged scale, of the central part of Fig. 6;

Fig. 8 is a fragmentary enlarged section on the line 8—8 of Fig. 7;

Fig. 9 is a fragmentary elevation showing a different form of the invention;

Fig. 10 is an enlarged fragmentary section on the line 10—10 of Fig. 9;

Fig. 11 is a perspective view of a part of the shelf structure shown in Fig. 9; and

Fig. 12 is a perspective detail of one of the article-supporting or storing members shown in Fig. 9.

The main objects of the invention are to provide in a refrigerator of any given total cubic content practically maximum capacity of storage, together with enhanced convenience in handling, for the number, size and shape of articles that may be in the refrigerator at any time, and for maintaining these conditions notwithstanding changes in the number, size and shape of stored articles from time to time, said objects of invention being accomplished by interchangeably varying the area, level and headroom of the various shelves and supports in practically all parts of the storage space within the refrigerator. The invention provides a plurality of supporting mem-

bers in side by side position and interchangeable with respect to each other and to supporting means on the refrigerator walls, said members having article-supporting surfaces of different areas and of such shape and size as to provide different available heights or headway capacities approximately just sufficient for the articles stored at any time in any part of the refrigerator. By arranging or rearranging the supporting members to best advantage a maximum of article-supporting areas and a minimum of waste headroom, together with increased accessibility or handling convenience, may be realized. The present preferred embodiment comprises a plurality of article-supporting devices of different areas, arranged side by side and also one above another as required or convenient, and carried directly or indirectly from the refrigerator walls, and shaped and proportioned, and also combinable to also provide different amounts or depths of headroom, dependent on the size and height of the articles to be stored. These supporting devices may be nested so as to provide a plurality of supporting areas at different levels and in vertical alinement and supported from the same points or levels in the refrigerator walls. In accordance with one feature of the invention, the various article-supporting devices may be independently moved into and out of the refrigerator space to enhance convenience in withdrawing and inserting articles. Further objects and features will be described later herein and it will be understood that the foregoing general description and the following detailed description are exemplary and explanatory, but are not restrictive of the invention.

Referring now in detail to the embodiment of the invention illustrated by way of example in the accompanying drawings, there is shown in Figs. 1 to 5 an embodiment of certain features of the invention, whereby a plurality of article-supporting or storing members are supported on a track-way structure which is itself supported on a refrigerator shelf, which may be of ordinary construction, the various supporting areas being in vertical alinement and individually slideable on the track-way into and out of the refrigerator, and preferably the track-way itself is likewise slideable inwardly and outwardly on the refrigerator shelf.

In the embodiment of said figures, a double trackway structure is provided above and below the refrigerator shelf, a plurality of article-supporting members, with their article-supporting areas at different levels, being slidably mounted in the upper track-way, and independently slideable thereon, a plurality of article-supporting members being slidably mountable in and suspended from the lower track-way structure. All the article-supporting members are interchange-

able, and may be of other shapes and sizes than those shown.

In said embodied form, a refrigerator 1 is shown with the door 2 thereof open, showing 5 the interior, which is provided with a suitable refrigerating unit 3. Mounted within the refrigerator is a shelf 8, which may be of the usual open cross bar or rod construction, and is carried upon suitable supports 10 at the sides of 10 the refrigerator and at or near the back end, devices 11 being also provided at the rear end to prevent the shelf from tipping up when the loaded article supports are drawn outwardly. Referring now to the construction details of the 15 embodied form of track-way shown in Figures 1 to 5, that is the double form already referred to, and in the upper track-way a side track member 16 is shown having track-ways 17 and 18 formed therein, also a corresponding side member 19 having track-ways 20 and 21 formed therein. Suitable cross pieces 24, 25 and 26 connect the side rails 16 and 19 across their ends and at 20 the middle part of their length. Similar side rails 27 and 28 for the lower track-way having, respectively, track-ways 29 and 30 and 31 and 32, are arranged to be positioned beneath the 25 refrigerator shelf, and are provided in like manner with cross bars 33, 34 and 35.

At their outer ends, the two track-ways are 30 hinged together, this being done by means of a pair of angled lugs 39 and 40 extending downwardly from cross-bar 26 and a like pair of lugs 41 and 42 extending upwardly from cross-bar 35 of the lower track-way. A hinge or pivot 35 rod 43 is mounted in apertures in the four lugs to permit the upper and lower track-ways to be opened apart, as shown in dot and dash lines in Fig. 2; and closed together as shown in solid lines in that figure. The track-way structure in 40 its open position is slipped inwardly with the refrigerator shelf between the two opened parts, and they are then closed together and fastened in horizontal position with the refrigerator shelf between them. The fastening means, as shown, 45 comprises a pair of lugs 49 and 50 extending downwardly from cross-bar 24 of the upper track-way, and a corresponding pair of lugs 51 and 52 extending upwardly from the cross-bar 33 of the lower track-way, the respective pairs of lugs being fastened together by bolts 53 and 54. Similar lug and bolt fastenings may be provided at 50 the intermediate cross-bars 25 and 34, are indicated by reference numeral 55, and need not be described in further detail. Suitable alining 55 and steadyng devices are provided on the inner pairs of cross-bars and as shown a lug 59 having a recess 60 therein extends downwardly from cross-bars 24 and 25 to embrace one of the rods of the refrigerator shelf to prevent the lateral displacement of the track-way, and a lug 61 extends upwardly from the cross-bar 33 to bear against the bottom side of one of the shelf rods to prevent vertical loose motion of the track-way structure.

In Figs. 1 and 2, an article-storing device 69 is 60 shown slidably mounted in the track-ways 18, 21 at the level of the track-ways having an article-supporting area 70, and side rods 71 and 72 intended to keep the articles away from the extreme side edges and from interference with the 65 upper article-supporting device which is independently slideable in the track-ways. The upper alined article-supporting device 74 has an open cross-barred article-supporting area 75 and protecting side rails 76 and 77. Its supports, such 70 as rods 78 fixed thereto at either side, extend

downwardly and connect, respectively, with horizontal rods 80 and 81, preferably part of a rectangular frame, and run in the track-ways 17 and 18. An article-storing device 83 is slidably mounted in, and suspended from, the lowermost 5 track-way 30, 31, the frame 84 running in the track-ways. Supporting rods 85 extend downwardly from frame 84 and form the open cross-bar supporting area 86. The entire track-way structure with all its article-supporting devices is 10 slideable to and fro for half the width of the shelf 9, as will be seen from Figs. 1 and 2. While only one such structure is shown in Fig. 1, it will be clear that a plurality of them could be mounted side by side at a common general level and 15 would provide independent side by side supporting areas, interchangeable to provide different supporting areas side by side and in vertical alinement also, with varying amounts of headroom as might be required while at the same 20 time providing a practical maximum of shelf area with very little wasted headroom.

In Figs. 6 to 8, inclusive, a somewhat different embodiment is shown, wherein the slideable track structure is provided for a plurality of nested and 25 vertically alined article carriers, with their supporting areas at different levels, which are slideably mounted in the track structure, and the track structure itself is slideable entirely into and out of a refrigerator shelf which may otherwise be 30 of ordinary type. The refrigerator shelf 90 is shown adapted to extend across the interior of the refrigerator and to be supported at a fixed level on the interior walls thereof. The shelf has a centrally located opening in which the slideable track-way is mounted, and at its rear edge the shelf has a frame rod 91, and at its front end it has a U-shaped reinforcing frame member 92 which may, if desired, be mounted as a bail in the members 93. The track-ways 94 and 95 in this 35 construction are connected together and spaced apart by rods 96 and 97 at either end of the tracks, and positioned so as not to interfere with the track-ways. The article carriers 101 and 102 are shown slideably mounted in the two upper 40 track-ways, and the article carrier 103 slideably suspended from the lowermost track-way, all three being in vertical alinement, but with their respective article-supporting areas 104 and 105 and 106 at different levels. By having the supporting means which are fixed to and extend from the supporting areas, such as rods 107 and 108, of different lengths, the relative levels of the supporting areas, and the headroom above each may be varied to suit the articles that may be stored 50 on any of the areas at any particular time. A plurality of these structures may be provided on one general level, if desired, and the size, level and relative positions of supporting areas, and the headroom above the various areas, may be 55 widely varied to give maximum storage, great accessibility with minimum waste of headroom.

In Figs. 9 to 12, inclusive, a somewhat different embodiment is shown, omitting the feature of the detachable slideable track-ways. In this embodiment a general shelf structure comprises a supporting frame having two spaced-apart supporting rods 114 and 115, with a plurality of spacing and supporting posts 116 between them, is adapted to fit within the refrigerator and to 60 rest upon suitable supports 117 fixed to the refrigerator walls with the rectangular rods practically abutting the inner walls of the refrigerator. A plurality of article-supporting or storing devices are shown, having supporting areas 75

118 and having upright supports 119 fixed to and extending therefrom and provided near their outer ends with means adapted to cooperate with the rods 114 and 115 to support the article-storing devices either above or below the rods 114 and 115. Suitable means are provided for supporting and interchanging the article-supporting devices, and for this purpose lugs 120 are fixed to the opposite or unattached ends of the supporting rods 119, and are supported upon either frame 114 or 115, and are slideable therealong, the members 114 and 115 being both supports and guideways. Thus the relative location of the supporting areas may be changed by sliding loaded supporting devices along the members 114 and 115 while light or unloaded supporting devices can be lifted out. In Fig. 9, the article-storing devices are shown arranged side-by-side, at different levels and giving four different amounts of headroom above the supporting area. It will be clear that the illustrated arrangement is exemplary, and that the article-storing devices are interchangeable with other sizes and forms, and by varying their sizes various ones may be also nested so as to give a plurality of vertically aligned supporting areas at different levels, at any desired point or location in the refrigerator, and to provide side-by-side supporting areas of different size and with varying amounts of headroom, as best suited to give maximum storage for the time being. The shelves, if desired, may be completely pulled out so that the combustibles will be completely outside the cabinet. Also, if desired, by employing suitable mechanism, the food containers could be rotated to positions entirely outside the cabinet, irrespective of the size and shape of the containers and the variations in the size thereof.

The invention in its broader aspects is not limited to the specific mechanisms shown and described but departures may be made therefrom within the scope of the accompanying claims without departing from the principles of the invention and without sacrificing its chief advantages.

5. What I claim is:

1. In a refrigerator, a general shelf structure extending across the interior, and supported from the side walls, of the refrigerator, said shelf structure comprising a plurality of separate members having interchangeable horizontal supporting areas disposable side by side, and having upright supports attached to and extending from said horizontal areas, said supports on the various shelf members being of different lengths, whereby contiguous side by side supporting areas may be at different levels with selectively variable amounts of headroom, said separate members being supportable by general shelf structure.

2. In a refrigerator, a general shelf structure extending across the interior, and supported from the side walls, said shelf structure comprising a plurality of separate members having horizontal supporting areas disposable side by side, and having upright supports attached to and extending from said horizontal areas, and connections whereby two contiguous side by side supporting areas may be one above and one below the level at which the shelf structure is supported with free headroom above each of said areas, said separate members being supportable by general shelf structure.

3. In a refrigerator, a general shelf structure extending across the interior, and supported from the side walls, said shelf structure comprising a

plurality of contiguous separate members having horizontal supporting areas disposable side by side, and having upright supports attached to and extending from said horizontal areas, said contiguous members being interchangeable to vary the level of contiguous horizontal supporting areas and to provide a plurality of areas in vertical alignment in accordance with the number, size and shape of articles to be stored, said separate members being supportable by general shelf structure.

4. In a refrigerator, a general shelf structure supported on the inner walls, and a plurality of side by side article-supporting devices, interchangeably supportable from said general shelf structure, said devices having horizontal supporting areas and upright supporting members fixed to and extending from the supporting areas and supportable at their opposite ends from said general shelf structure, whereby supporting areas may be provided at different desired levels with respect to said general shelf structure to vary the headroom above said supporting areas.

5. In a refrigerator having a general shelf structure supported on the inner walls, a shelf located at a permanent level therewithin, and a plurality of article-supporting devices, concurrently supportable from said general shelf structure, said devices having horizontal supporting areas and upright supporting members fixed to and extending from said supporting areas and supportable at their opposite ends by said general shelf structure, whereby supporting areas may be concurrently provided at different desired levels with respect to said general shelf structure to vary the headroom above said supporting areas.

6. In a refrigerator having a general shelf structure supported on the inner walls, a shelf member located at a permanent level therewithin, and a plurality of article-supporting devices, concurrently supportable from said general shelf structure, said devices having horizontal supporting areas and upright supporting members fixed to and extending from said supporting areas, and supportable at their opposite ends by said general shelf structure, with one supporting device nested within another to present supporting areas in vertical alignment and at different levels.

7. In a refrigerator, a track-way, means for supporting the track-way from the refrigerator walls, a plurality of interchangeable article-carriers slidably supported upon said track-way and detachable from the track-way, said article-carriers having supporting areas at different distances from the track-way to provide varying headroom above different carriers.

8. In a refrigerator, a track-way, means for supporting the track-way from the refrigerator walls, a plurality of interchangeable article-carriers slidably supported upon said track-way and detachable from the track-way, said article-carriers having supports of different heights, and means upon said supports for slidably engaging the track-way to provide varying headroom above different carriers.

9. In a refrigerator, supports on the refrigerator walls, a track-way removably carried by said supports, and a plurality of article-carriers arrangeable side by side and also one above another and slidably and removably mounted on said track-way.

JOHN T. WHALEN.
